TOOL HANDLE EXTRACTOR

Filed Oct. 3, 1927

Inventor

Edgar Warren Smith

By *Clarence O'Brien*
Attorney

UNITED STATES PATENT OFFICE.

EDGAR WARREN SMITH, OF KEENE, NEW HAMPSHIRE.

TOOL-HANDLE EXTRACTOR.

Application filed October 3, 1927. Serial No. 223,695.

My invention relates to improvements in tool handle extractors, and the purpose of the same is to facilitate the removal of worn or broken handles from tool heads.

5 My device is particularly useful for quickly removing handles from axes where heretofore considerable effort and exertion was required.

10 In lumber camps and in other places where axes are used, considerable time is spent in removing the handles from the ax heads. Not only is my extractor very useful for removing ax heads, but it is equally effective in removing pick handles, hammer handles, and 15 in fact all tool handles, the tool head of which being wedged on the handle in the usual well known manner.

10 An object of my invention is to provide such a tool handle extractor which will be 20 simple in construction to allow a low cost of manufacture, but at the same time providing such an extractor which will be very effective for the purpose desired, and which in the construction will be very durable.

25 Other objects and advantages will become apparent as my invention is better understood from the specification and claims to follow.

In the drawing:—

30 Figure 1 represents a side elevation, showing my improved handle extractor with a tool and handle in position, with respect thereto.

Fig. 2 is an end elevation of the device, as 35 represented in Fig. 1, and

Fig. 3 is a perspective view of the plate and threaded follower forming part of my invention.

40 For a more detailed description of my invention, I now refer to the drawings, in which like numerals designate like parts. The rectangular shaped plate 1 is formed with a threaded opening through approximately the center of the same. Openings 2 formed 45 through the plates substantially inwardly from the four corners thereof, are adapted to have projected upwardly therethrough, the threaded blade portion 3 of a pair of U-shaped supporting members 4. The threaded 50 portions of the U-shaped supporting members are provided with nuts 5 threaded thereon, adapted to bear on the top surface of the

plate to adapt the slippage of the leg members of the U-shaped parts downwardly through the openings therein.

55 The centrally located threaded opening in the plate has threaded therein a follower screw 6, at the lower end of which is secured a follower plate 7, which may be of suitable shape in construction, to conform to the work to which it may be applied. The upper end of the screw is provided with a squared enlargement 8.

An L-shaped bracket member 9 is formed with suitable openings in the vertical extent 65 of same, while the base portion thereof, is securely riveted or fastened by other means in this plate 1.

As is clearly shown in Fig. 1 of the drawings, in the operation of extracting an ax 70 handle from the ax head, the U-shaped supporting members 4 are removed from association with the plates. The ax head designated at 10 is placed between the leg members of the respective supporting members so that the 75 handle thereof will extend downwardly as shown.

The projecting portions of the ax head are allowed to rest on the bight portion of said U-shaped part. The screw section is then 80 screwed to position as shown in Fig. 1, and the threaded legs of the support are then threaded upwardly through their respective openings in the plate, the nuts 5 are then threaded on the end portions of the legs to 85 prevent the support from slipping downwardly from its secured position in respect to the plate.

The follower plate 7 is then brought to bear against the end of the handle, located in the 90 head of the tool. By screwing the follower screw downwardly through the plate, the follower 95 7 will force the handle from its position in a tool head. The device may be secured to a wall or other structure by the L-shaped bracket 9.

Having thus described my invention, what I claim as new is:—

In a tool handle extractor comprising a plate, a pair of U-shaped members, said U-shaped members having their respective end portions threaded, the threaded end portions of said U-shaped members adapted for slideable disposition through openings in said

plate, nuts adapted to be threaded on the threaded end portions of the U-shaped members for drawing the bight portions of the members toward the plate for securing a tool

5 head between the respective bight portions of the U-shaped members, and the adjacent side of the plate, a bolt threadable through

the plate between the U-shaped members, and a head on one end of the bolt for engagement with the end of the tool handle located within 10 the tool head for extracting the same.

In testimony whereof I affix my signature.

EDGAR WARREN SMITH.
